UNITED STATES PATENT OFFICE.

WILLIAM F. SPRINGER, OF EDWARDSVILLE, ILLINOIS.

FLOWER-POT DRAINER.

SPECIFICATION forming part of Letters Patent No. 611,523, dated September 27, 1898.

Application filed December 15, 1897. Serial No. 662,039. (No model.)

To all whom it may concern:

Be it known that I, WILLIAM F. SPRINGER, a citizen of the United States, residing at Edwardsville, in the county of Madison and State of Illinois, have invented a new and useful Flower-Pot Drainer, of which the following is a specification.

The invention relates to improvements in flower-pot drainers.

10 The object of the present invention is to provide a simple, inexpensive, and efficient device adapted to be readily arranged within a flower-pot over the opening in the bottom thereof and capable of insuring perfect and 15 uniform drainage, and thereby facilitating the growing of plants.

The invention consists in the construction and novel combination and arrangement of parts, as hereinafter fully described, illustrated in the accompanying drawings, and pointed out in the claims hereto appended.

20 In the drawings, Figure 1 is a detail perspective view of a device constructed in accordance with this invention. Fig. 2 is a 25 similar view showing the lower face thereof. Fig. 3 is a vertical sectional view showing the device applied to a flower-pot.

Like numerals of reference designate corresponding parts in the several figures of the 30 drawings.

1 designates a disk or plate designed to be arranged within a flower-pot 2 over the opening in the bottom thereof to obstruct partially the passage of water through the same, 35 and the said plate or disk, which preferably has a convex upper face 3, is provided with inclined side edges 4, extending inward from the upper face 3 to the bottom of the disk or plate. The convex upper face 3 prevents 40 any water from collecting upon the device and remaining within the flower-pot and the inclined sides 4 serve to reduce the area of the bottom or lower face of the disk or plate and bring the water closer to the opening 5 in the bottom of the pot. The disk or plate is provided at its upper face with an outwardly-projecting peripheral flange 1^a, forming a continuance of the upper convex face 3; but a flat-topped plate of circular or any 45 other shape may be employed, if desired.

In practice the device is designed to be covered with coarse sand, which also fills the

space between it and the sides of the flower-pot, and in order to permit water to drain freely from the flower-pot the device is provided at its side edges with a series of grooves or gutters 6, extending from the upper face 3 of the disk or plate to the lower face thereof and gradually increasing in width toward the latter. The lower face of the disk or 55 plate is provided with a central annular recess 7, with which the grooves or gutters 6 communicate, and a depending stud 8 is arranged at the center of the annular recess 7 and is adapted to fit in the opening 5 of the 60 flower-pot to center the device on the bottom thereof, the stud only partially filling the opening to permit a free flow of the water in 65 draining.

The grooves or gutters 6, which are radially disposed, as clearly illustrated in Fig. 2 of the accompanying drawings, form lugs or feet, and the alternate spaces between the radial grooves or gutters are provided with an outer series of short grooves 9 and an inner 75 recess 10, which increase the drainage of the flower-pot.

The invention has the following advantages: The device is simple and comparatively inexpensive in construction, it requires 80 no skill to arrange it within a flower-pot, and it will insure perfect and uniform drainage. Its convex upper face is adapted to shed water perfectly and prevent the same from accumulating upon the device and remaining 85 in the flower-pot, and the grooves or gutters permit the water to flow freely to the opening of the flower-pot.

Changes in the form, proportion, and minor details of construction may be resorted to 90 without departing from the spirit or sacrificing any of the advantages of this invention.

What I claim is—

1. A device of the class described consisting of an imperforate disk provided at its lower 95 face with a series of gutters, and having lugs or feet located between the gutters and adapted to rest upon the bottom of the flower-pot, said feet or lugs being provided at their lower faces with a series of short grooves, substantially as described.

2. A device of the class described, consisting of an imperforate plate designed to rest upon the bottom of a flower-pot and cover the open-

ing thereof and provided with a depending stud adapted to fit in the said opening and prevent the plate from becoming displaced, said plate being provided with passages extending to the stud, substantially as described.

3. A device of the class described consisting of an imperforate plate provided at its lower face with a depending stud and having a recess extending around the same, said plate being provided with a series of gutters or grooves extending from the said recess over the bottom and side faces, substantially as described.

4. A device of the class described consisting of an imperforate disk having a convex upper face and provided with inclined side edges extending inward from the upper face to the lower face, said lower face having a central recess and provided with radial gutters or grooves, substantially as described.

5. A device of the class described, consisting of an imperforate disk or plate provided at its lower face with a central recess and having a series of radial grooves or gutters, said plate being provided at intervals between the radial grooves or gutters with an outer series

of short grooves and an inner recess, substantially as described.

6. A device of the class described consisting of an imperforate disk or plate having a convex upper face and inclined side edges and provided at its lower face with a central recess and with gutters or grooves extending radially from the same, said plate having a stud depending from the said recess and adapted to fit in the opening in the bottom of a flower-pot, substantially as and for the purpose described.

7. A device of the class described consisting of an imperforate plate provided at its top with a projecting flange and having gutters or grooves extending inward from its side edges to the center of its lower face, substantially as described.

In testimony that I claim the foregoing as my own I have hereto affixed my signature in the presence of two witnesses.

WILLIAM F. SPRINGER.
